Primary Examiner — Thomas E Lazo(57) **ABSTRACT**

To achieve improvement of operability and reduction of energy loss, when controlling so that an upper limit pressure of a discharge line becomes a pressure corresponding to an manipulation tool manipulation amount by controlling an increase or decrease of a bypass amount, in a hydraulic control circuit equipped with a bypass valve for controlling a bypass amount flowing from a hydraulic pump to an oil tank. By using a bypass valve control map representing a relationship between a manipulation tool manipulation amount and a spool stroke of a bypass valve is controlled, and an upper limit pressure of the discharge line is set so that an opening area of the bypass valve is fully closed by a manipulation amount which is larger than a manipulation tool manipulation amount at which the maximum pressure of the discharge line is reached.

HYDRAULIC CONTROL CIRCUIT**CROSS-REFERENCE TO RELATED APPLICATION**

This Application is a 35 USC § 371 US National Stage filing of International Application No. PCT/EP2021/025145 filed on Apr. 19, 2021 which claims priority under the Paris Convention to Japanese Patent Application No. 2020-080129 filed on Apr. 30, 2020.

TECHNICAL FIELD

The present invention relates to a technical field of a hydraulic control circuit for a work machine such as a hydraulic excavator.

BACKGROUND ART

In general, a hydraulic control circuit of a work machine such as a hydraulic excavator is configured to include a hydraulic pump; a hydraulic actuator to which a pressure oil is supplied from the hydraulic pump; a manipulation tool that is manipulated so as to actuate the hydraulic actuator; and a control valve that is connected to a discharge line of the hydraulic pump, and configured to perform oil supply and discharge control to/from the hydraulic actuator in accordance with the manipulation of the manipulation tool; and a main relief valve configured to set a maximum pressure of the discharge line, etc. Furthermore, there are some hydraulic control circuits provided with a bypass oil passage (bleed oil passage) that is formed so as to be branched from the discharge line and reaches an oil tank, in order to adjust the pressure of the discharge line of the hydraulic pump; and a bypass valve (bleed valve) that is disposed in the bypass oil passage, and controls a bypass amount (bleed amount) flowing from the hydraulic pump to the oil tank in response to a control signal that is output from a control device (see, for example, Patent Literatures 1, 2 and 3).

Such a bypass valve is controlled so that the opening area decreases, that is, the bypass amount decreases with an increasing manipulation amount of the manipulation tool. In this case, the hydraulic control circuit disclosed in Patent Literature 1 is configured such that the opening area of the bypass valve is controlled so as to follow a flow rate curve that is set beforehand, as a function of the stroke of the control valve (operation valve). Further, the hydraulic control circuit disclosed in Patent Literature 2 is configured to control a movement stroke of the bypass valve by using a table representing a relationship between a manipulation signal of the manipulation tool and a spool movement stroke of the bypass valve. Further, the hydraulic control circuit disclosed in Patent Literature 3 is configured to cause the opening area of the bypass valve to be proportionally decreased with an increasing manipulation amount.

SUMMARY OF THE INVENTION

5

Problems to be Solved by the Invention

Meanwhile, in such a hydraulic control circuit as described above, the maximum pressure of the discharge line of the hydraulic pump is set by the main relief valve, while the upper limit pressure of the discharge line is adjusted by controlling the increase and decrease of the opening area of the bypass valve corresponding to the manipulation tool manipulation amount. For this reason, when controlling the opening area of the bypass valve, it is necessary to consider a relationship between a maximum pressure of the discharge line set by the main relief valve and an upper limit pressure of the discharge line adjusted by the bypass valve. However, any of the hydraulic control circuits disclosed in the above Patent Literatures 1 to 3 has not considered the above-described relationship. For this reason, a manipulation tool manipulating region in which the upper limit pressure can be adjusted by the bypass valve might be narrowed, resulting in impairing the operability, and oil might continue to flow from the bypass valve to the oil tank even after the discharge line reaches the maximum pressure, resulting in energy loss.

Furthermore, when the pressure of the discharge line of the hydraulic pump is high, for the bypass valve of a spool type, oil might leak from the bypass valve, depending on an overlapping length between a land portion of the spool of the bypass valve and a sliding contact portion of a housing with which the land part comes into sliding contact, even when the bypass valve is fully closed, and these are problems to be solved by the present invention.

Means for Solving the Problems

The present invention has been created with an aim of solving these problems in view of the above actual situations. A hydraulic control circuit for a work machine according to Claim 1 of the present invention comprises a hydraulic pump; a hydraulic actuator to which a pressure oil is supplied from the hydraulic pump; a manipulation tool that is manipulated so as to actuate the hydraulic actuator; a control valve that is connected to a discharge line of the hydraulic pump, and configured to perform oil supply and discharge control to/from the hydraulic actuator, in accordance with the manipulation of the manipulation tool; a main relief valve configured to set a maximum pressure of the discharge line; a bypass oil passage that is formed so as to be branched from the discharge line and reaches an oil tank; and a spool type bypass valve disposed on the bypass oil passage, and configured to control a bypass amount flowing from the hydraulic pump to the oil tank in response to a control signal that is output from a control device,

wherein, the bypass valve is configured such that an opening area increases or decreases associated with displacement of the spool, in controlling so that an upper limit pressure of the discharge line becomes a pressure corresponding to a manipulation tool manipulation amount by controlling an increase or decrease of a bypass amount in accordance with a manipulation tool manipulation amount; on the other hand, the control device is provided with a map representing a relationship between a manipulation tool manipulation amount and a spool displacement amount, and controls

the spool displacement amount of the bypass valve as a function of the manipulation tool manipulation amount, on the basis of the map; and the map is set such that the upper limit pressure of the discharge line is a pressure corresponding to a spool displacement amount that causes the opening area of the bypass valve to be fully closed by a manipulation amount larger than the manipulation tool manipulation amount at which the maximum pressure of the discharge line is reached.

A hydraulic control circuit for a work machine according to Claim 2 of the present invention is the hydraulic control circuit according to Claim 1, configured to control the spool displacement amount as a function of the manipulation tool manipulation amount by using the map even in the fully closed state of the bypass valve, in order to control an overlapping length between a land portion of the spool of the bypass valve and a sliding contact portion of a housing with which the land portion comes into sliding contact in the fully closed state of the bypass valve.

A hydraulic control circuit for a work machine according to Claim 3 of the present invention is the hydraulic control circuit according to Claim 2, wherein the control device is configured to vary the overlapping length between the land portion of the spool and the sliding contact portion of the housing in the fully closed state of the bypass valve according to the pressure of the discharge line, by inputting a signal from a pressure detecting means for detecting the pressure of the discharge line of the hydraulic pump and varying the map according to the input pressure of the discharge line.

Favorable Effects of the Invention

According to Claim 1 of the present invention, the manipulating region of the hydraulic actuator manipulation tool can be made as wide as possible where the increase or decrease of the upper limit pressure can be controlled by the bypass valve, which can contribute to improvement of operability and reduction of energy loss.

According to Claim 2 of the present invention, it is possible to control an overlapping length between the land portion of the spool in the fully closed state and the sliding contact portion of the housing with which the land portion comes into sliding contact.

According to Claim 3 of the present invention, it is possible to prevent oil leakage from the bypass valve by increasing the overlapping length even when the discharge line is high.

BRIEF DESCRIPTION OF THE DRAWINGS

FIG. 1 is a hydraulic control circuit diagram of a first embodiment.

FIG. 2 is a diagram representing a relationship between a spool stroke and a bypass valve opening area in the first embodiment.

FIG. 3 is a block diagram illustrating input/output of a controller in the first embodiment.

FIG. 4: (A) is a diagram illustrating a bypass valve control map of the first embodiment, and (B) is a diagram illustrating a relationship between a manipulation tool manipulation amount and an upper limit pump pressure.

FIG. 5 is a diagram illustrating changes in the bypass valve control map in the first embodiment.

FIG. 6 is a hydraulic control circuit diagram of a second embodiment.

FIG. 7 is a diagram representing a relationship between a spool stroke and a bypass valve opening area in the second embodiment.

FIG. 8 is a diagram illustrating a bypass valve control map of the second embodiment.

FIG. 9 is a diagram illustrating changes in the bypass valve control map in the second embodiment.

DETAILED DESCRIPTION OF THE INVENTION

Hereinafter, embodiments of the present invention will be described with reference to the drawings.

First, a first embodiment of the present invention will be described with reference to FIGS. 1 to 5. FIG. 1 is a schematic illustration of a hydraulic control circuit for a hydraulic excavator which is an example of a work machine. In FIG. 1, reference numeral 1 denotes a variable capacity type hydraulic pump driven by an engine E; reference numeral 1a denotes a capacity-varying means of the hydraulic pump 1; reference numeral 2 denotes a discharge line of the hydraulic pump 1; reference numeral 3 is denotes an oil tank; reference numeral 4 denotes a hydraulic actuator that operates as an oil pressure supply source by using the hydraulic pump 1; reference numeral 5 denotes a pilot-operated control valve that performs control of oil supply and discharge to/from the hydraulic actuator 4; reference numerals 6A, 6B denote a first and a second electromagnetic proportional pressure-reducing valves that output a pilot pressure so as to operate the control valve 5.

The hydraulic excavator is provided with various types of hydraulic actuators such as a boom cylinder, a stick cylinder, a bucket cylinder, a traveling motor, and a swivel motor, and provided with respective control valves in association with respective hydraulic actuators, besides provided with electromagnetic proportional pressure-reducing valves that output a pilot pressure to operate the respective control valves. In FIG. 1, however, on behalf of these hydraulic actuators, control valves, and electromagnetic proportional pressure-reducing valves, there are only illustrated one hydraulic actuator (hydraulic cylinder) 4 and a control valves 5 corresponding to the hydraulic actuator 4, a first and a second electromagnetic proportional pressure-reducing valves 6A, 6B corresponding to the control valve 5, and two other control valves 5 corresponding to two other hydraulic actuators (not illustrated) respectively.

The control valve 5 is a closed center type spool valve, and is configured to include a first and a second pilot ports 5a, 5b respectively connected to the first and second electromagnetic proportional pressure-reducing valves 6A, 6B; a pump port 5c connected to the discharge line 2 of the hydraulic pump 1; a tank port 5d connected to the oil tank 3; and a pair of actuator ports 5e, 5f respectively connected to respective ports 4a, 4b of the hydraulic actuator 4. Further, the control valve 5 is configured such that, in a state where no pilot pressure is input to both the first and second pilot ports 5a, 5b, the spool is located at a neutral position N at which the pump port 5c, the tank port 5d, and the pair of actuator ports 5e, 5f are closed; however, when the pilot pressure is input from the first or second electromagnetic proportional pressure-reducing valve 6A or 6B to the first or second pilot port 5a or 5b, the spool is switched to a first operating position X or a second operating position Y at which a supply flow passage 5g extending from the pump port 5c to one actuator port 5e or 5f, and a discharge flow passage 5h extending from the other actuator port 5f or 5e to

5

the tank port **5d** are opened to perform supply flow rate control and discharge flow rate control to/from the hydraulic actuator **4**.

In the present embodiment, each of the control valves **5** is connected in parallel with respect to the hydraulic pump **1**, and a check valve **9** is disposed in oil passage on an upstream side of the pump port **5c** of each of the control valves **5** to hold a load pressure of the hydraulic actuator **4**.

Furthermore, in FIG. 1, reference numeral **10** denotes a pilot primary side oil passage for supplying a pilot primary pressure to the first and second electromagnetic proportional pressure-reducing valves **6A**, **6B**, and the pilot primary side oil passage **10** is formed so as to be branched from the discharge line **2** of the hydraulic pump **1** via a pressure-reducing valve **11**. That is, the pressure-reducing valve **11** reduces pressure of the hydraulic pump **1**, which is a common oil pressure supply source with the hydraulic actuator **4**, to generate a predetermined pilot primary pressure P_p to the first and second electromagnetic proportional pressure-reducing valves **6A**, **6B** via the pilot primary side oil passage **10**. However, in the pilot primary side oil passage **10**, a check valve **12** for holding the pilot primary pressure P_p and an accumulator **13** for smoothing the pilot primary pressure are disposed in this order from the upstream side (the pressure-reducing valve **11** side). The first and second electromagnetic proportional pressure-reducing valves **6A**, **6B** do not output the pilot pressure in a non-operating state, but operate in response to a control signal that is output from the controller **15**, which will be described below, to reduce the input pilot primary pressure P_p and output it to the first and second pilot ports **5a**, **5b** of the control valve **5**. Then, the control valve **5** is designed to be switched from the neutral position **N** to the first operating position **X** or the second operating position **Y**, as described above, by the pilot pressure that is output from the first and second electromagnetic proportional pressure-reducing valves **6A**, **6B**, and to perform the supply flow rate control and the discharge flow rate control to/from the hydraulic actuator **4**. In this case, the pilot pressure that is output from the first, second electromagnetic proportional pressure-reducing valves **6A**, **6B** is controlled to increase or decrease in accordance with the manipulation amount of the hydraulic actuator manipulation tool (corresponding to the manipulation tool of the present invention) **21** by the controller **15**. The spool displacement amount of the control valve **5** increases or decreases in accordance with the increase or decrease of the pilot pressure, so that an increase or decrease of the opening areas of the supply flow passage **5g** and the discharge flow passage **5h** is controlled, thereby performing the control of the increase or decrease of the supply flow rate and the discharge flow rate.

A hydraulic actuator manipulation tool **21** and a manipulation detecting means **22** for detecting the manipulation (manipulation amount and manipulation direction) of the hydraulic actuator manipulation tool **21** are respectively provided in association with respective hydraulic actuators, but FIG. 1 illustrates only the manipulation tool **21** and the manipulation detecting means **22** corresponding to one hydraulic actuator **4**.

Furthermore, in FIG. 1, reference numeral **16** denotes a main relief oil passage that is formed so as to be branched from the discharge line **2** of the hydraulic pump **1** and reaches the oil tank **3**, and a main relief valve **17** configured to set a maximum pressure (system pressure) of the discharge line **2** is disposed in the main relief oil passage **16**.

6

Furthermore, in FIG. 1, reference numeral **18** denotes a bypass oil passage that is formed so as to be branched from the discharge line **2** of the hydraulic pump **1** and reaches the oil tank **3**, and in the bypass oil passage **18**, there is disposed a bypass valve (bleed valve) **19** configured to control a bypass amount (bleed amount) flowing from the hydraulic pump **1** to the oil tank **3** via the bypass oil passage **18**. The bypass valve **19** comprises an inlet side port **19a** connected to the hydraulic pump **1**, an outlet side port **19b** connected to the oil tank **3**, and a housing (not illustrated) having these inlet side and outlet side ports **19a**, **19b**, a spool **19c** inserted into the housing so as to be freely movable in an axial direction, a spring **19d** that is provided on one end side of the spool **19c** and urges the spool **19c** to an initial position, and a proportional solenoid **19e** that is provided on the other end side of the spool **19c** and causes the spool **19c** to move against an urging force of the spring **19d**, and the like. Further, the bypass valve **19** is configured such that the pilot primary pressure P_p acts on the other end side of the spool **19c** via an introduction oil passage **20** that is formed so as to be branched from the pilot primary side oil passage **10**. Then, the stroke (displacement amount from the initial position) of the spool **19c** is controlled to increase or decrease by controlling the increase or decrease of a current value applied to the proportional solenoid **19e** as a control signal from the controller **15**, and the bypass amount flowing from the hydraulic pump **1** to the oil tank **3** via the bypass oil passage **18** is controlled in accordance with the opening areas of the bypass valve **19** corresponding to the stroke.

Meanwhile, a relationship between a stroke and an opening area of the spool **19c** of the bypass valve **19** will be described with reference to FIG. 2. In a state in which no electric current is applied to the proportional solenoid **19e**, the spool **19c** is located at the initial position (stroke "0") by the urging force of the spring **19d**, but at the initial position, the opening area of the bypass valve **19** is set to be an initial opening area A_f that is smaller than a setting opening area A_s , which will be described below. Then, the spool **19c** is displaced from the initial position by an electric current that is applied to the proportional solenoid **19e**, and the stroke of the spool **19c** increases with an increasing electric current value applied to the proportional solenoid **19e**. In this case, the opening area is maintained at the initial opening area A_f until the stroke reaches the first stroke S_1 from the initial position, and the opening area decreases as the stroke increases until reaching the second stroke S_2 ($S_1 < S_2$) from the first stroke S_1 , and when reaching the second stroke S_2 , the opening area of the bypass valve **19** is set to "0", that is, to be fully closed. Then, this fully closed state (opening area $A=0$) is maintained after the stroke increases from the second stroke S_2 until reaching a third stroke S_3 ($S_2 < S_3$). Furthermore, when the stroke of the spool **19c** increases from the third stroke S_3 , the bypass valve **19** is opened. In this case, however, the opening area also increases as the stroke increases, and the opening area reaches the setting opening area A_s which is larger than the initial opening area A_f and is slightly smaller than the maximum opening area A_m when the stroke reaches a fourth stroke S_4 ($S_3 < S_4$) before the stroke reaches a maximum stroke S_m . Furthermore, the opening area reaches a maximum opening area A_m when the stroke reaches a fifth stroke S_5 ($S_4 < S_5$) which is slightly moved from the fourth stroke S_4 , and the maximum opening area A_m is maintained until reaching the maximum stroke S_m ($S_5 < S_m$) from the fifth stroke S_5 . In FIG. 2, a sixth stroke S_6 is a stroke ($S_2 < S_6 < S_3$) between the

second stroke S2 and the third stroke S3 at which the opening area is maintained at "0". The stroke S6 will be described below.

On the other hand, the controller (which corresponds to the control device of the present invention) 15, as illustrated in the block diagram of FIG. 3, is configured to input signals from the manipulation detecting means 22 for respectively detecting the manipulations of respective hydraulic actuator manipulation tools 21, and the pump pressure sensor (which corresponds to the pressure detecting means of the present invention) 23 for detecting the pressure (pump pressure) of the discharge line 2 of the hydraulic pump 1, the engine controller 24, etc., and to output control signals to the first, second electromagnetic proportional pressure-reducing valves 6A, 6B, the proportional solenoid 19e of the bypass valve 19, the capacity-varying means 1a of the hydraulic pump 1, etc., in response to these input signals, and is provided with a bypass valve control map (which corresponds to a map of the present invention) 25 as will be described below.

The stroke of the spool 19c of the bypass valve 19 is controlled in accordance with a current value applied from the controller 15 to the proportional solenoid 19e as described above. However, the control of the stroke of the bypass valve 19 by the controller 15 will be described. First, before the engine E is started, no electric current is applied from the controller 15 to the proportional solenoid 19e, and the bypass valve 19 is located at the initial position by an urging force of the spring 19d. Furthermore, the opening area of the bypass valve 19 at the initial position is set to an initial opening area Af as described above. The initial opening area Af is set to an opening area (Af<As) smaller than the setting opening area As as described above, which is a minimum opening area necessary for causing the discharge oil of the hydraulic pump 1 to escape into the oil tank 3 immediately after the engine is started, in order to prevent the pump pressure from rapidly rising immediately after the start of the drive of the hydraulic pump 1 associated with the engine start and prevent an excessive load from being applied to the engine E.

On the other hand, when the engine E starts and the hydraulic pump 1 starts driving accordingly, an electric current is not applied from the controller 15 to the proportional solenoid 19e of the bypass valve 19 and the spool 19c is maintained at the initial position, that is, the opening area of the bypass valve 19 is maintained at the initial opening area Af, until the pump pressure detected by the pump pressure sensor 23 reaches a required pressure Po. This will enable preventing a rapid rise in the pump pressure immediately after the start of the engine drive, and will enable making a pump pressure rising speed until reaching a required pressure Po faster, compared with the case where the opening area of the bypass valve at the time of starting the engine is set to the maximum opening area (for example, a case like the bypass valve 33 in the second embodiment described below). The required pressure Po is a value larger than the pilot primary pressure Pp so that a predetermined pilot primary pressure Pp can be supplied from the hydraulic pump 1 to the pilot primary side oil passage 10, and a small value, for example about 4 Mpa, is desirable from the viewpoint of energy saving.

Then, after the pump pressure reaches the required pressure Po, the controller 15 applies an electric current to the proportional solenoid 19e so that the stroke of the spool 19c reaches a fourth stroke S4, in a state in which a manipulation signal is not input from the manipulation detecting means 22, that is, in a state in which the hydraulic actuator

manipulation tool 21 is not manipulated (the manipulation tool is at the neutral position). This will enable the opening area of the bypass valve 19 to reach a setting opening area As. The setting opening area As, however, is an opening area at which the pressure of the discharge line 2 is maintained at a pressure of the order of the required pressure Po, and an opening area larger than the initial opening area Af, in a state in which the discharge amount of the hydraulic pump 1 is of the order of a predetermined amount, and as described above, when the engine speed E is of the order of a predetermined speed (for example, rated speed). Further, until the pump pressure reaches the required pressure Po from the start of the engine E, the controller 15 will not output a control signal of actuation to the first and second electromagnetic proportional pressure-reducing valves 6A, 6B even if the hydraulic actuator manipulation tool 21 is manipulated, so that the control valve 5 is to be held in the neutral position N at which the pressure oil is not supplied to the hydraulic actuator 4. Furthermore, when the manipulation signal is not input from the manipulation detecting means 22 for a predetermined time or more, the controller 15 applies an electric current to the proportional solenoid 19e so that the stroke of the spool 19c becomes the fifth stroke S5, and sets an opening area of the bypass valve 19 to the maximum opening area Am. This will enable reduction of pressure loss of the bypass oil passage 18 in a case where the hydraulic actuator manipulation tool 21 is not manipulated for a predetermined time or longer.

Meanwhile, as described above, it is configured such that the pilot primary pressure Pp acts on the other end side (opposite side of 19d) of the spool 19c of the bypass valve 19 via the introduction oil passage 20 that is formed so as to be branched from the pilot primary side oil passage 10. For this reason, when the pressure of the discharge line 2 is lowered below the required pressure Po and becomes less than the pilot primary pressure Pp, while the hydraulic actuator manipulation tool 21 is not manipulated, the pilot pressure acting on the other end side of the spool 19c of the bypass valve 19 becomes smaller, and the spool 19c moves in a direction in which the stroke decreases from the fourth stroke S4 or the fifth stroke S5. This will enable making adjustment so that the opening area of the bypass valve 19 decreases and the pressure of the discharge line 2 reaches the required pressure Po.

Further, the bypass valve 19, as described above, is located at an initial position by the urging force of the spring 19d, in a state where no electric current is applied to the proportional solenoid 19e from the controller 15, and the opening area of the bypass valve 19 at the initial position is set to the initial opening area Af. As a result, even granted that malfunction occurs in the bypass valve 19 due to certain defects in an electrical system extending from the controller 15 to the proportional solenoid 19e, the bypass oil passage 18 would be opened by the bypass valve 19, and a rapid rise in the pump pressure at the start of the engine or non-startable state of not starting the engine could be avoided, and since the initial opening area Af, which is an opening area of the bypass valve 19 in this case, is an opening area that is smaller than the setting opening area As that is an opening area of the bypass valve 19 when the manipulation tool is at the neutral position, the pressure of the discharge line 2 will also rise above the required pressure Po when the manipulation tool is at the neutral position, and it becomes possible to perform minimum operations necessary for emergency evacuation of the work machine and the like, even if the bypass valve 19 ceases to operate.

Next, the control of the bypass valve 19 in a case where the hydraulic actuator manipulation tool 21 is manipulated after the engine E is started and the pump pressure reaches the required pressure P_o will be described. In this case, the controller 15 controls the stroke of the spool 19c by using a bypass valve control map 25, which will be described below.

The bypass valve control map 25, as illustrated in FIG. 4(A), is a map representing a relationship between a manipulation amount of the hydraulic actuator manipulation tool 21 (manipulation tool manipulation amount) that is input from the manipulation detecting means 22 and a stroke of the spool 19c, which is set for each hydraulic actuator 4. For example, in a hydraulic excavator, respective bypass valve control maps 25 are individually set with respect to respective hydraulic actuators, such as extension side and retraction side of a boom cylinder, extension side and retraction side of a stick cylinder, extension side and retraction side of a bucket cylinder, a traveling motor, and a swivel motor. This bypass valve control map 25 is created as a map that represents a relationship between a manipulation tool manipulation amount and a stroke of the spool 19c, by determining an opening area of the bypass valve 19 for setting the upper limit pressure of the discharge line 2 to the upper limit pressure corresponding to the manipulation tool manipulation amount, and further by determining a stroke of the spool 19c at which the relevant opening area is reached, so that a relationship between a manipulation tool manipulation amount and an upper limit pressure of the discharge line 2 (the pressure of the discharge line 2 when the pressure oil is not supplied to the hydraulic actuator 4 because the piston is located at the cylinder end, for example) becomes a relationship of beforehand-set pressure characteristics. In this case, the relationship of the beforehand-set pressure characteristics, as illustrated in FIG. 4(B), is set so that the upper limit pump pressure (upper limit pressure of the discharge line 2) reaches the system pressure (the maximum pressure, for example 35 MPa, of the discharge line 2 set by the main relief valve 17) when the manipulation tool manipulation amount is a first manipulation amount L_1 ; and in the bypass valve control map 25, as illustrated in FIG. 4(A), the relationship of the beforehand-set pressure characteristics is set to reach a third stroke S_3 when the opening area of the bypass valve 19 becomes "0" at a second manipulation amount L_2 which is slightly increased larger than the first manipulation amount L_1 . In this case, the stroke of the spool 19c is controlled so that the change in the opening area during the time until the opening area of the bypass valve 19 becomes "0" after the upper limit pump pressure reaches the system pressure is performed smoothly associated with the increase of the manipulation tool manipulation amount from the first manipulation amount L_1 to the second manipulation amount L_2 .

It may be better to perform special control in some cases, for example, to control the upper limit pump pressure so as to be lower than the system pressure at boom lowering of the hydraulic excavator. In such a case, the opening area of the bypass valve 19 is set so as to avoid "0" even when the manipulation tool manipulation amount is maximal.

When the control of the bypass valve 19 by the controller 15 using the bypass valve control map 25 is described with reference to FIG. 4(A), in a state where the hydraulic actuator manipulation tool 21 is not manipulated (the manipulation tool manipulation amount is "0", the manipulation tool at the neutral position), the spool 19c is controlled to stay at the fourth stroke S_4 , as described above. Then, when the hydraulic actuator manipulation tool 21 is manipulated, the spool 19c is controlled to move in a direction in

which the stroke decreases as the manipulation tool manipulation amount increases, that is, in a direction in which the opening area of the bypass valve 19 decreases; and when manipulation tool manipulation amount is manipulated up to the second manipulation amount L_2 , the spool 19c is controlled so that the stroke reaches the third stroke S_3 at which the opening area of the bypass valve 19 becomes "0". Furthermore, the controller 15 controls the stroke of the spool 19c in accordance with the increase in the manipulation tool manipulation amount even after the opening area of the bypass valve 19 becomes "0".

The stroke of the spool 19c when the opening area of the bypass valve 19 becomes "0", that is, an electric current value applied to the proportional solenoid 19e corresponding to the position of the third stroke S_3 is desirably corrected by calibration or the like.

Further, in an interlocking operation in which a plurality of hydraulic actuators 4 are simultaneously operated, the stroke of the spool 19c of the bypass valve 19 is calculated on the basis of the manipulation amounts of respective hydraulic actuator manipulation tools 21 that is input from the manipulation detecting means 22 and the bypass valve control maps 25 for respective hydraulic actuators.

Meanwhile, the control of the stroke of the spool 19c after the opening area of the bypass valve 19 becomes "0" will be described with reference to a partial enlarged view of the bypass valve control map 25 illustrated in FIG. 5. The controller 15 changes the bypass valve control map 25 in response to the present pump pressure of the discharge line 2 that is input from the pump pressure sensor 23, after the opening area of the bypass valve 19 becomes "0". In this case, when the pump pressure that is input from the pump pressure sensor 23 is higher than a setting pressure which is beforehand set (for example, 35 MPa), even after the stroke of the spool 19c reaches the third stroke S_3 at which the opening area of the bypass valve 19 becomes "0", as illustrated by the solid line in FIG. 5, the stroke of the spool 19c is set to decrease as the manipulation tool manipulation amount increases, that is, to be displaced toward the second stroke S_2 direction. When the manipulation tool manipulation amount reaches the maximum (maximum manipulation amount L_m), the spool 19c is controlled so as to stay at a sixth stroke S_6 which is an intermediate stroke between the third stroke S_3 and the second stroke S_2 . The sixth stroke S_6 is located in between the third stroke S_3 at which the opening area of the bypass valve 19 is maintained at "0" and the second stroke S_2 , which is a position at which an overlapping length between a land portion of the spool 19c and a sliding contact portion of the housing that comes into sliding contact with the land portion is the longest. The spool 19c staying at the sixth stroke S_6 can reliably prevent oil leakage from the bypass valve 19 even when the pump pressure is high.

On the other hand, when the pump pressure that is input from the pump pressure sensor 23 becomes lower than the setting pressure, the bypass valve control map 25 is changed so that the displacement in a direction from the third stroke S_3 toward the second stroke S_2 after the opening area of the bypass valve 19 has become "0", decreases as the pump pressure becomes low, and is set so that, when the pump pressure is sufficiently low (for example, 5 MPa), the spool 19c is located at the third stroke S_3 , even when the manipulation tool manipulation amount reaches a maximum manipulation amount L_m , as illustrated by the dotted line in FIG. 5. As a result, when the pump pressure is low enough to prevent the risk of leakage of the spool 19c, the spool 19c will be immediately moved in a direction of the fourth stroke

11

S4 to open the opening of the bypass valve 19 with a decreasing manipulation amount of the manipulation tool, resulting in good responsiveness of the bypass valve 19 to the manipulation of the manipulation tool.

In the present embodiment configured as described above, the hydraulic control circuit of the hydraulic excavator is configured to include a hydraulic pump 1; a hydraulic actuator 4 to which a pressure oil is supplied from the hydraulic pump 1; a hydraulic actuator manipulation tool 21 manipulated in order to actuate the hydraulic actuator 4; a control valve 5 connected to the discharge line 2 of the hydraulic pump 1, and configured to perform oil supply/discharge control to/from the hydraulic actuator 4, in accordance with the manipulation of the hydraulic actuator manipulation tool 21; a main relief valve 17 configured to set a maximum pressure of the discharge line 2; a bypass oil passage 18 that is formed so as to be branched from the discharge line 2 and reaches an oil tank 3; a spool type bypass valve 19 disposed on the bypass oil passage 18, and configured to control a bypass amount flowing from the hydraulic pump 1 to the oil tank 3 in response to a control signal that is output from the controller 15, and so on. In this hydraulic control circuit, the bypass valve 19 is configured such that the opening area increases or decreases associated with the displacement of the spool 19c, in controlling so that the upper limit pressure of the discharge line 2 becomes a pressure corresponding to the manipulation tool manipulation amount, by controlling increase or decrease of the bypass amount as a function of the manipulation amount of the hydraulic actuator manipulation tool 21; on the other hand, the controller 15 is provided with a bypass valve control map 25 representing a relationship between a manipulation tool manipulation amount and a spool stroke (displacement amount of the spool 19c), and controls the spool stroke of the bypass valve 19 as a function of the manipulation tool manipulation amount, on the basis of bypass valve control map 25; and in the bypass valve control map 25, the upper limit pressure of the discharge line 2 is set to become a pressure corresponding to the spool stroke (the third stroke S3 in the first embodiment) at which the opening area of the bypass valve 19 is fully closed by a second manipulation amount L2 which is a manipulation amount larger than a first manipulation amount L1 at which the maximum pressure of the discharge line 2 is reached.

Therefore, the displacement amount of the spool 19c of the bypass valve 19 is controlled in accordance with the manipulation tool manipulation amount by using the bypass valve control map 25. The upper limit pressure of the discharge line 2 will be controlled to become a pressure corresponding to the manipulation amount of the hydraulic actuator manipulation tool 21, in accordance with the increase or decrease of the opening area of the bypass valve 19 associated with the displacement of the spool 19c; in this case, however, the upper limit pressure of the discharge line 2 will be controlled so that the opening area of the bypass valve 19 is fully closed at the second manipulation amount L2 which is a larger manipulation amount than the first manipulation amount L1 at which the maximum pressure of the discharge line 2 is reached. As a result, until the upper limit pressure of the discharge line 2 reaches the maximum pressure of the discharge line 2, the upper limit pressure of the discharge line 2 will be able to be controlled to become a pressure corresponding to the manipulation tool manipulation amount, by controlling the increase/decrease of the opening area of the bypass valve 19, and the manipulating region of the hydraulic actuator manipulation tool 21 can be made as wide as possible where the increase or decrease of

12

the upper limit pressure can be controlled by the bypass valve 19, which can greatly contribute to the improvement of operability. On the other hand, when the upper limit pressure of the discharge line 2 is controlled so that the bypass valve 19 is fully closed when the manipulation amount becomes larger than when the maximum pressure of the discharge line 2 is reached, thereby attaining the reduction of energy loss.

Furthermore, in this the hydraulic control circuit, it is configured such that the stroke of the spool 19c with respect to the manipulation tool manipulation amount is controlled by the bypass valve control map 25 even in a state where the bypass valve 19 is fully closed, thereby enabling the control of the overlapping length between the land portion of the spool 19c (in a state where the bypass valve 19 is fully closed) and the sliding contact portion of the housing with which the land portion comes into sliding contact. In this case, it is configured such that a signal from the pump pressure sensor 23 that detects the pressure of the discharge line 2 of the hydraulic pump 1 is input to the controller 15, and the overlapping length is changed in accordance with the pressure of the discharge line 2, by changing the bypass valve control map 25 in accordance with the input pressure of the discharge line 2. This will enable preventing oil leakage from the bypass valve 19 by increasing the overlapping length even when the discharge line 2 has a high pressure, resulting in contribution to the reduction of energy loss.

Next, the second embodiment of the present invention will be described with reference to FIGS. 6 to 9. Elements in the second embodiment identical to those in the first embodiment are designated by the same reference numerals and therefore a description thereof will be omitted.

FIG. 6 is a diagram illustrating an outline of the hydraulic control circuit of the second embodiment. In FIG. 6, reference numeral 30 denotes a pilot pump driven by the engine E, and the pilot primary pressure generated by the pilot pump 30 is supplied to the first and second electromagnetic proportional pressure-reducing valves 6A, 6B that output the pilot pressure to the control valve 5, via a pilot primary side oil passage 31 connected to the pilot pump 30. In other words, in the second embodiment, the hydraulic pump 1 which serves as an oil pressure supply source of the hydraulic actuator 4 and the pilot pump 30 which supplies the pilot primary pressure to the first and second electromagnetic proportional pressure-reducing valves 6A, 6B are separately provided. In FIG. 6, reference numeral 32 denotes a pilot relief valve for setting a circuit pressure of the pilot primary side oil passage 31.

Furthermore, in FIG. 6, reference numeral 33 denotes a bypass valve according to the second embodiment, and the bypass valve 33 is disposed in the bypass oil passage 18 which is formed so as to be branched from the discharge line 2 of the hydraulic pump 1 and reaches the oil tank 3, similarly to the first embodiment. Then, the bypass amount flowing from the hydraulic pump 1 to the oil tank 3 via the bypass oil passage 18 will be controlled by the bypass valve 33, and the bypass valve 33 includes an inlet side port 33a connected to the hydraulic pump 1, an outlet side port 33b connected to the oil tank 3, a housing (not illustrated) having these inlet side and outlet side ports 33a, 33b, a spool 33c inserted into the housing so as to be freely movable in the axial direction, a spring 33d provided on one end side of the spool 33c and urging the spool 33c to the initial position, a proportional solenoid 33e provided on the other end side of the spool 33c, causing the spool 33c to move against the urging force of the spring 33d, and the like. Then, an

13

increase or decrease of a stroke (displacement amount from the initial position) of the spool 33c is controlled, in accordance with an increase or decrease control of an electric current value applied from the controller 15 to the proportional solenoid 33e. The bypass amount flowing from the hydraulic pump 1 to the oil tank 3 via the bypass oil passage 18 is controlled, in accordance with the opening area of the bypass valve 33 corresponding to the stroke.

Meanwhile, the relationship between the stroke of the spool 33c of the bypass valve 33 and the opening area in the second embodiment will be described with reference to FIG. 7. When no electric current is applied to the proportional solenoid 33e, the spool 33c is located at an initial position (stroke “0”) by the urging force of the spring 33d, but at the initial position, the opening area of the bypass valve 33 is set to become a maximum opening area Am. Then, the spool 33c is displaced from the initial position due to an electric current being applied to the proportional solenoid 33e, and the stroke of the spool 33c increases with increasing current value applied to the proportional solenoid 33e. In this case, however, the opening area is maintained at the maximum opening area Am until the stroke reaches the first stroke S1 from the initial position, and the opening area is set to decrease as the stroke increases from the first stroke S1, and when the stroke reaches the second stroke S2 (S1<S2), the opening area A of the bypass valve 33 is set to “0”, that is, to be fully closed. Then, this fully closed state (opening area A=0) will be maintained until the stroke further increases from the second stroke S2 and reaches the maximum stroke Sm (S2<Sm).

The stroke of the spool 33c of the bypass valve 33 is controlled in accordance with a current value applied from the controller 15 to the proportional solenoid 33e, but the control of the stroke of the bypass valve 33 by the controller 15 will be described. First, no electric current is applied to the proportional solenoid 33e from the controller 15, before the engine E is started, and the bypass valve 33 is located at an initial position by the urging force of the spring 33d. Furthermore, the opening area of the bypass valve 33 at the initial position is set to the maximum opening area Am as described above.

Furthermore, when the hydraulic actuator manipulation tool 21 is not manipulated, after the engine E is started, no electric current is applied to the proportional solenoid 33e from the controller 15, and the bypass valve 33 is maintained at the initial position, that is, the maximum opening area Am by the urging force of the spring 33d. On the other hand, when the hydraulic actuator manipulation tool 21 is manipulated, the controller 15 controls the stroke of the spool 33c of the bypass valve 33 by using a bypass control map 34 of the second embodiment.

The bypass valve control map 34, as illustrated in FIG. 8, is a map illustrating the relationship between the manipulation amount (manipulation tool manipulation amount) of the hydraulic actuator manipulation tool 21 that is input from the manipulation detecting means 22 and the stroke of the spool 33c, and is respectively set for each of the hydraulic actuators 4 and created in the same manner as in the first embodiment. In this case, however, the upper limit pump pressure (pump pressure in a state where a pressure oil is not supplied to the hydraulic actuator 4) when the manipulation tool manipulation amount is kept at the first manipulation amount L1 is set to reach the system pressure (the maximum pressure of the discharge line 2 set by the main relief valve 17) (see FIG. 4(B)), and when the manipulation tool manipulation amount is kept at the second manipulation amount L2 which is slightly increased larger than the first

14

manipulation amount L1, the stroke is set to become the second stroke S2 at which the opening area of the bypass valve 33 becomes “0”. In this case, the stroke of the spool 33c is controlled so that change in the opening area during 5 the time until the opening area of the bypass valve 33 becomes “0” after the pump pressure having reached the system pressure is smoothly performed associated with an increase of the manipulation tool manipulation amount from the first manipulation amount L1 to the second manipulation amount L2, similarly to the first embodiment.

The control of the bypass valve 33 by the controller 15 using the bypass valve control map 34 will be described with reference to FIG. 8. In a state where the hydraulic actuator manipulation tool 21 is not manipulated (the manipulation tool manipulation amount “0”, the manipulation tool at the neutral position), the stool 33c is controlled so as to stay at an initial position at which the opening area becomes the maximum opening area Am, as described above. Then, when the hydraulic actuator manipulation tool 21 is manipulated, 10 the spool 33c is controlled so as to be displaced in a direction in which the stroke increases with an increasing manipulation tool manipulation amount, that is, in a direction in which the opening area of the bypass valve 33 decreases; and when the manipulation tool manipulation amount is 15 manipulated up to the second manipulation amount L2, the spool 33c is controlled so as to reach the second stroke S2 at which the opening area of the bypass valve 33 becomes “0”. Furthermore, the controller 15 controls the stroke of the spool 33c in accordance with the increase in the manipulation tool manipulation amount, similarly to the first embodiment, even after the opening area of the bypass valve 33 has become “0”.

Meanwhile, the control of the stroke of the spool 33c after the opening area of the bypass valve 33 has become “0” will 20 be described with reference to a partial enlarged view of the bypass valve control map 34 illustrated in FIG. 9. The controller 15 changes the bypass valve control map 34 in response to the present pump pressure of the discharge line 2 that is input from the pump pressure sensor 23, even in the second embodiment, after the opening area of the bypass valve 33 has become “0”. In this case, when the pump pressure that is input from the pump pressure sensor 23 is 25 higher (for example, 35 MPa) than the setting pressure which is set beforehand, even after the stroke of the spool 33c reaches the second stroke S2 at which the opening area of the bypass valve 33 becomes “0”, as illustrated by the solid line in FIG. 9, the stroke of the spool 33c increases as the manipulation tool manipulation amount increases, that is, the spool 33c is set to be displaced in a direction of the maximum stroke Sm, and the spool 33c is set to reach the maximum stroke Sm when the manipulation tool manipulation amount becomes the maximum (maximum manipulation amount Lm). At the maximum stroke Sm, the overlapping length between the land portion of the spool 19c and the sliding contact portion of the housing that comes into 30 sliding contact with the land portion is formed to be the longest, thereby reliably preventing oil leakage from the bypass valve 19 even when the pump pressure is high.

On the other hand, when the pump pressure that is input 35 from the pump pressure sensor 23 becomes lower than the setting pressure, the bypass valve control map 34 is changed so that the displacement in a direction from the second stroke S2 toward the maximum stroke Sm after the opening area of the bypass valve 33 has become “0”, decreases as the pump pressure becomes low, and is set so that, when the pump pressure is sufficiently low (for example, 5 MPa), the spool 33c is located at the second stroke S2, even when the

15

manipulation tool manipulation amount reaches a maximum manipulation amount L_m , as illustrated by the dotted line in FIG. 9. As a result, when the pump pressure is low enough to prevent the risk of leakage of the spool 33c, the spool 33c will be immediately moved in a direction of the first stroke S1 to open the opening of the bypass valve 33 with a decreasing manipulation amount of the manipulation tool, resulting in good responsiveness of the bypass valve 33 to the manipulation of the manipulation tool.

Therefore, the bypass valve 33 of the second embodiment adopts a configuration in which the opening area decreases with an increase of the stroke of the spool 33c, and the spool stroke of the bypass valve 33 increases as the manipulation amount of the hydraulic actuator manipulation tool 21 increases. Although the spool stroke is configured to increase, even in the second embodiment in which the bypass valve 33 configured in this way is used, the upper limit pressure of the discharge line 2 will be controlled so that the opening area of the bypass valve 19 is fully closed, at the second manipulation amount L_2 which is larger than the first manipulation amount L_1 at which the discharge line 2 reaches the maximum pressure, which will exhibit the same action and effect as those of the first embodiment, thereby contributing to the improvement of operability and the reduction of energy loss.

INDUSTRIAL APPLICABILITY

The present invention can be utilized to control a bypass valve provided in a hydraulic control circuit of a work machine such as a hydraulic excavator.

The invention claimed is:

1. A hydraulic control circuit for a work machine, the hydraulic control circuit comprising: a hydraulic pump; a hydraulic actuator to which a pressure oil supplied from the hydraulic pump; a manipulation tool that is manipulated so as to actuate the hydraulic actuator, a control valve that is connected to a discharge line of the hydraulic pump, and configured to perform oil supply and discharge control to/from the hydraulic actuator, in accordance with the manipulation of the manipulation tool; a main relief valve configured to set a maximum pressure of the discharge line; a bypass oil passage that is formed so as to be branched from the discharge line and reaches an oil tank; and a spool type

16

bypass valve disposed on the bypass oil passage, and configured to control a bypass amount flowing from the hydraulic pump to the oil tank in response to a control signal that is output from a control device.

wherein, the bypass valve is configured such that an opening area increases or decreases associated with displacement of the spool, in controlling so that an upper limit pressure of the discharge line becomes a pressure corresponding to a manipulation tool manipulation amount by controlling an increase or decrease of a bypass amount in accordance with a manipulation tool manipulation amount; the control device is provided with a map representing a relationship between a manipulation tool manipulation amount and a spool displacement amount, and controls the spool displacement amount of the bypass valve as a function of the manipulation tool manipulation amount, on the basis of the map; and the map is set such that the upper limit pressure of the discharge line is a pressure corresponding to a spool displacement amount that causes the opening area of the bypass valve to be fully closed by a manipulation amount larger than the manipulation tool manipulation amount at which the maximum pressure of the discharge line is reached,

wherein the control device is configured to vary the overlapping length between a land portion of the spool of the bypass valve and a sliding contact portion of a housing in the fully closed state of the bypass valve

according to the pressure of the discharge line, by inputting a signal from a pressure detecting means for detecting the pressure of the discharge line of the hydraulic pump and varying the map according to the input pressure of the discharge line.

2. The hydraulic control circuit for a work machine according to claim 1, configured to control the spool displacement amount as a function of the manipulation tool manipulation amount by using the map even in the fully closed state of the bypass valve, in order to control an overlapping length between the land portion of the spool of the bypass valve and the sliding contact portion of a housing with which the land portion comes into sliding contact in the fully closed state of the bypass valve.
